UNITED STATES PATENT OFFICE.

CHARLES T. SLEEPER AND FREDERICK J. HUBBARD, OF CHICAGO, ILLINOIS,
ASSIGNORS TO THE SLEEPER MANUFACTURING COMPANY, OF SAME
PLACE.

METALLIC PACKING FOR PISTON AND VALVE RODS.

SPECIFICATION forming part of Letters Patent No. 334,480, dated January 19, 1886.

Application filed October 22, 1885. Serial No. 180,605. (No model.)

To all whom it may concern:

Be it known that we, CHARLES T. SLEEPER and FREDERICK J. HUBBARD, of Chicago, in the county of Cook and State of Illinois, have 5 invented certain new and useful Improvements in Metallic Packing for Piston and Valve Rods; and we do hereby declare the following to be a full, clear, and exact description of the invention, such as will enable others skilled in 10 the art to which it appertains to make and use the same.

Our invention relates to an improvement in metallic packing for piston and valve rods and more especially relates to an improvement 15 in the metallic packing for which Letters Patent No. 300,653 were granted to Charles T. Sleeper, June 17, 1884.

The object of the invention is to prevent any leakage of steam between the metallic 20 packing and its seat, and to obviate any unequal or uneven pressure or wear of the metallic packing-rings on the piston or valve rod, due to unequal expansion and contraction of the different kinds of metal or alloy of which the 25 parts of the packing are made.

A further object is to retain the metallic packing in proper adjustment, so that it shall not wear unevenly by reason of its weight resting on the rod.

30 A further object is to provide for the self-adjustment of the packing in any direction, and thereby accommodate it to the different adjustments of the piston or valve rod.

A further object is to provide an improved 35 construction of metallic packing-rings, and also other features of improvement, as will hereinafter be explained.

With these ends in view our invention consists in certain features of construction and 40 combinations of parts, as will be hereinafter described, and pointed out in the claims.

In the accompanying drawings, Figure 1 is 45 a plan view of the outer face of our improved packing. Fig. 2 is a similar view of the inner face or side of the same. Fig. 3 is a view in elevation with the section *b* of the casing removed. Fig. 4 is a sectional view. Fig. 5 is a detached view, in perspective, of the cam-ring. Fig. 6 is a view in perspective of one

of the metallic packing-sections. Fig. 7 is a 50 plan view of a ring made up of two sections, and Fig. 8 is an edge view of one of the rings.

A represents a box or casing, consisting of the two halves or sections *a b*, which are secured together by means of screws *a'*, inserted 55 in screw-threaded holes formed in the outwardly-projecting lugs *a'*; or the sections may be fastened together in any other manner desired. The inner periphery of the box or casing A is constructed with an annular 60 groove, B, in which is located a cam-ring, C, the latter being loosely fitted, so as to freely rotate therein. Cam-ring C may be provided on its inner periphery with any desired number of cams, *c*. In the drawings the ring is 65 shown as being provided with five cam projections. The periphery of the cam-ring is provided with cogs or worm-teeth *c'*, with which engages the worm *c*² on the shaft *c*³, which latter is journaled in half-bearings formed in 70 the projection D on the outer surface of the casing. Worm-shaft *c*³ is made square or of requisite shape at its outer end for the attachment of a wrench, so that by turning it the cam-ring may be rotated in either direction. 75

E represents the followers, each of which consists of an arc-shaped plate, *d*, having short arms *d' d'* projecting rearwardly therefrom, the arm *d'* entering a groove, *d*³, formed 80 in section *b* of the casing, and the arm *d'*, entering a groove, *d*⁴, in the section *a*.

Opposite each one of the cams *c* is located a follower, E. By rotating the cam-ring the cams *c* will engage the rear face of each one 85 of the followers and simultaneously force all of them radially inward, for tightening the packing-ring, as will hereinafter appear. The metallic packing-ring is seated on a metal ring, *e*, which forms a seat or bearing, and is 90 supported on the flange *e'* of the bushing F. Packing-ring G is composed of four sections, *g*, which are the counterpart of one another. Each section *g* consists of a segmental wearing portion, *g'*, made slightly less than one-half of 95 a circle, so that a space, *g*², will be formed between the adjacent ends of the sections, to admit of the contraction of the rings as worn, to

cause them to snugly fit the piston-rod. On the rear side of the wearing portion g' of each section is formed a segmental plate or projection, g^2 , which is slightly less than double the width of the wearing portion g' , while it is less in length, so that when the sections are put together the rear plate or projections, g^2 , will form the outer periphery of the ring. A space, g^4 , is formed between the adjacent ends of the rear plates, to permit of the contraction of the rings. Thus it will be observed that the four metallic sections when put together form a single metallic packing-ring, the inner periphery of which is composed of two sectional wearing-rings capable of expansion and contraction, while the outer periphery of the ring is composed of four segments, constructed and arranged to overlap the joints of the wearing-sections, and forming broad bearings for the engagement of the yielding band which retains the sections in place. The segmental plates or portions g^2 on the rear side of the wearing portion g' of each section are each provided with kerfs or slots d^4 , which are preferably formed in the process of casting the sections, and are made of any desired depth or width. The object of these kerfs is to weaken that portion of each section provided with the segmental plates or portions g^2 to such an extent that it will bend when pressure is applied thereto as readily as the projecting ends of the wearing portions, and thus cause the wearing portions to bend uniformly throughout their entire length and snugly fit the piston-rod when the packing-ring is contracted in diameter. Yielding band H is made of two sections, $h\ h$, of spring metal, one section being arranged within the other to break joints, and the outer section having outwardly-projecting spurs h' , which engage with one of the followers, to prevent the rotation of the band when in use. The yielding band encircles the packing-ring and retains its sections against displacement, and enables the sectional packing-ring to be readily removed and replaced. The band also serves as a bearing for the followers in contracting the ring. Against the outer surface of the packing-ring is placed a follower, I , which is constructed with a flange, i , that projects outwardly, enabling the follower to be grasped by the hand and readily removed. J represents a ring, which screws into the outer section of the box or casing and engages the follower I . By adjusting the ring I , which may be done by inserting a pin into any one of the holes j , formed in said ring J , it may be turned in either direction, and any desired pressure thereby exerted on the packing-ring. The screw-ring is constructed with a ratchet on its periphery, with which engages a pawl, j' , pivoted to the box or casing, which serves to prevent the rotary displacement of the ring.

Another locking device may be used in lieu of the pawl and ratchet.

K is a face-plate, which is seated against the end of the stuffing-box cast on the cylinder-

head or steam-chest, and is secured in place by means of the studs K' , which are connected to the stuffing-box. Recesses K^2 are formed in the outer surfaces of the face-plate, near its ends, for the reception of the angular bosses K^3 on the studs. Face-plate K has cast thereon an annular flange, K^4 , which enters the opening of the stuffing-box, and thereby retains the face-plate in position. Around the flange K^4 is formed a seat, K^5 , between which and the end of the stuffing-box is placed a suitable gasket for packing the joint steam-tight. Within the annular flange of the face-plate is placed a bushing, F , which prevents the rod from coming in contact with the iron of the face-plate, and also forms a seat for the ring e , which is ground upon its face to form a steam-tight joint with the bushing, and also forms an inner bearing or seat for the metallic packing-ring. The inner section, a , of the box or casing is provided with arms $L\ L$, each of which is formed with an elongated slot, l , having formed thereon a ledge or seat, l' . Studs K on the stuffing-box project through the elongated slots l , and, being slightly less in diameter than the width of the slots, the arms $L\ L$ are allowed both lateral and vertical movement. Bosses K^3 on the studs K' are received within recesses L in the face-plate, and serve to fasten the latter to the stuffing-box. Over the projecting ends of the studs K' are placed the washers M , which seat upon the ledges l' within the slotted arms. Spiral springs N encircle the studs and rest on the washers M . Against the outer ends of the spiral springs are placed the disks O , through the perforations of which are inserted the screw-bolts P , which are screwed into the ends of the studs. By applying a wrench to the heads of the screw-bolts the disks O are forced snugly against the outer ends of the studs K' , thereby compressing the spiral springs between the disks O and the washers M . The studs K' project slightly beyond the outer surface of the arms L , thereby insuring a space between the disks and the arms, to allow of a limited movement of the latter and the box and casing toward and from the face-plate. As the springs are seated at their outer ends against the disks O , which form a rigid bearing therefor, the tension of the springs will be exerted against the washers M and force the latter in snug frictional contact with their supporting-ledges in the slotted arms, and thereby tend to force the box or casing toward the face-plate. On the other hand, the box or casing is drawn away from the face-plate by means of the screw-ring J , owing to the fact that the latter has a bearing on the metal packing-ring, which is supported by the bushing in the face-plate; hence by screwing the ring into the box or casing the latter is drawn outwardly against the force of the spiral springs N , thereby maintaining the casing in suspension and retaining it in lateral and vertical adjustment by the frictional contact of the washers M on their supporting-ledges and

the frictional contact of the ring Q on its seat, due to the pressure exerted on the metallic packing supported or seated on the ring. This feature of our improvement is important and valuable, for several reasons.

In metallic packings capable of lateral and vertical adjustment the construction of parts has been such that the weight of the packing-rings and box or casing is supported by the piston-rod, the effect of which is to cause the metallic packing to wear unevenly, the upper sides thereof wearing away more rapidly than their lower sides. In our improved construction we obviate this defect by supporting the self-adjusting box or casing, with its contained metallic packing, by the frictional contact of the washers M with their supporting-ledges in the slotted arms, and also the frictional contact of the ring e on its seat, caused by the tension of the spiral springs. The frictional contact of the parts described is not sufficient to prevent the free vertical and lateral adjustments of the box or casing, so that it may readily accommodate itself to the piston or valve rod and at all times be in alignment therewith, but is sufficient to support the weight of the box or casing, and thereby relieve the piston-rod itself and insure an even and uniform wear of the metallic packing. Again, we accomplish another important result by our improved yielding attachment of the box or casing to the face-plate.

In the use of this type of metallic packing it has been found impossible to preserve a steam-tight joint at all times between the inner face or rear face of the metallic packing-ring and its seat when the box or casing is secured to the face-plate, so as not to admit of any endwise movement thereof, owing to the fact that the coefficient of expansion and contraction of the alloy of which the packing-ring is composed differs quite materially from that of the metal of which the box or casing is formed. When the packing-ring is confined within a box or casing rigidly secured to the face-plate, and the adjusting-nut turned down to set up the packing-ring, the latter, when heated, will tend to expand to a greater degree than the cast metal of which the box or casing is made, and as no provision is made to allow of such unequal expansion the packing-ring will be compressed and contracted in its length, and when allowed to cool off will open a space between its inner or rear face and seat for the escape of steam.

By means of our improvement we obviate the defects and objectionable features above specified by the employment of the yielding connection between the face-plate and box or casing. The springs tend to force the box or casing toward the face-plate, while the screw-ring operates to draw the box or casing away from the face-plate in opposition to the power of the springs, and thus the box or casing is retained in a state of suspension by the screw-ring. When the metallic packing-ring expands, due to its becoming heated, the box or

casing will yield outwardly from the face-plate against the tension of the springs N, and thereby accommodate the uneven expansion of the packing-rings, as compared with that of the box or casing, and allow the rings to expand longitudinally, or in the direction of the length of the box or casing, and thus prevent any compression or lengthwise contraction of the packing-ring, so that when the latter cools off, causing it to contract, the spring will take up for such contraction by drawing the box or casing toward the face-plate, and preserve a steam-tight joint between the packing-ring and its seat. Thus by our improvement we insure an even and uniform pressure of the metallic packing-ring on its piston or valve rod throughout the different range of heat and cold to which the metallic packing may be subjected.

The arc-shaped plates of the followers E are made of spring metal, to allow of their yielding, and thus insure a uniform and even pressure on the periphery of the packing-ring when pressure is applied thereto for contracting it and forcing it against the piston-rod. It will be observed that the followers are wholly enclosed within the box or casing, and hence we obviate the necessity for opening through the casing, and thereby prevent the ingress of dust to the packing.

While we have described the box or casing as being applied to a face-plate, we may in certain cases dispense with the face-plate described, and by inserting a suitable bushing in the stuffing-box, and dressing off the end of the latter and bushing, mount the box or casing directly on the end of the stuffing-box; hence when mention is made in the claims of a face-plate we would have it understood that by such term we include and cover the construction last specified as well.

As it is evident that many slight changes in the construction and arrangement of the different parts of our improved metallic packing might be made without departing from the spirit or scope of our invention, we would have it understood that we do not limit or restrict ourselves to the particular features of construction and arrangement of parts shown; but

Having fully described our invention, what we claim as new, and desire to secure by Letters Patent, is—

1. In a metallic packing, the combination, with a box or casing provided with metallic packing, of devices for securing the box or casing to its face-plate and allowing the box to adjust itself toward and from said face-plate, substantially as set forth.

2. In a metallic packing, the combination, with a box or casing and metallic packing located within said casing and supported on a seat or bearing connected with the face-plate, of yielding fastenings for connecting the box or casing to the face-plate, substantially as set forth.

3. In a metallic packing, the combination,

- with a box or casing, metallic packing located therein, and means connected with the box or casing for adjusting the packing, of devices for connecting the box or casing in a yielding manner to the cylinder or steam-chest, substantially as set forth.
4. In a metallic packing, the combination, with a box or casing containing metallic packing, of springs and adjusting-nuts for securing the box or casing to the face-plate and allowing it to yield both laterally and vertically, substantially as set forth.
5. In a metallic packing, the combination, with a box or casing containing metallic packing, of springs and adjusting-nuts for securing the box or casing to the face-plate, so as to allow said box or casing to be self-adjusting in a lateral, vertical, and forward and backward direction, substantially as set forth.
- 20 6. In a metallic packing, the combination, with a box or casing, a metallic packing contained therein and supported on a seat connected with the face-plate, and devices for imparting both radial and endwise adjustment to the metallic packing, of yielding devices for fastening the box or casing to the face-plate, and thereby allowing the box or casing to be self-adjustable in any direction, substantially as set forth.
- 30 7. In a metallic packing, the combination, with the studs connected with the cylinder or steam-chest, of a box or casing containing the metallic packing and provided with slotted arms for reception of said studs, and springs and adjusting-nuts for securing the box or casing in place in a yielding manner, substantially as set forth.
- 35 8. In a metallic packing, the combination, with the box or casing having slotted arms, of studs extending into said slotted arms, washers or plates resting on flanges in the slots, springs seated on the washers, and screw-bolts, said parts being constructed and arranged to secure the box or casing to the face-plate, substantially as set forth.
- 40 9. The combination, with the studs on the stuffing-box and screw-bolts adapted to be screwed into the outer ends of the studs, of a box or casing provided with slotted arms adapted to receive said studs and springs interposed between the heads of the screw-bolts and the arms, substantially as set forth.
- 45 10. In a metallic packing, the combination, with the box or casing and a cam-ring located therein, of followers located wholly within the box or casing and adapted to be actuated by said cam-ring, substantially as set forth.
- 50 11. In a metallic packing, the combination, with a box or casing, metallic packing located therein, followers for contracting the ring, and devices for imparting simultaneous movement to the followers, of a screw-ring

for imparting endwise adjustment to the packing and a pawl for locking the screw-ring against rotary displacement, substantially as set forth.

12. In a metallic packing, the combination, with a face-plate and a box or casing secured thereto, of a sectional metallic packing located within the box or casing, a screw-ring for holding the metallic packing in place, provided with ratchet-teeth, and a pawl engaging said teeth, substantially as set forth.
13. In a metallic packing, the combination, with the box or casing, metallic packing contained therein, and a screw-ring, of a follower-ring provided with an outwardly-projecting flange, substantially as set forth.
14. In a metallic packing, the combination, with the sectional metallic packing-ring, of a sectional yielding band provided with outwardly-projecting spurs, substantially as set forth.
15. In a metallic packing, the combination, with the box or casing containing the sectional metallic packing-ring, of a face-plate provided with an annular flange adapted to enter the outer end of the stuffing-box, substantially as set forth.
16. A metallic packing-ring composed of sections, each of which is constructed to overlap the wearing portions of two adjacent sections, substantially as set forth.
17. A metallic packing-ring constructed of sections, each of which is composed of a wearing portion and of a rear overlapping portion or plate, the latter being double or nearly double the width of the wearing portions, substantially as set forth.
18. A metallic packing-ring composed of sections having kerfs or slots formed in their outer sides.

19. In a metallic packing, the combination, with a laterally-adjustable box or casing having a metallic packing-ring located therein, of a screw-ring for forcing the packing-ring against its seat and drawing the box or casing away from the face-plate, substantially as set forth.

20. In a metallic packing, the combination, with a laterally-adjustable box or casing having metallic packing contained therein, of a screw-ring, and springs arranged to allow the packing-ring to be self-adjusting under variations in temperature, and to retain it in place by the frictional contact with the adjacent parts, substantially as set forth.

In testimony whereof we have signed this specification in the presence of two subscribing witnesses.
